CLAIM

The ornamental design for a crib, as shown and described.

DESCRIPTION

FIG. 1 is a front perspective view of the crib, showing the new design;

FIG. 2 is front view of the crib;

FIG. 3 is a rear view of the crib;

FIG. 4 is a left view of the crib;

FIG. 5 is a right view of the crib;

FIG. 6 is a top view of the crib; and,

FIG. 7 is a bottom view of the crib.

Surface lines are used in the drawings. The surface lines are not to be understood as conveying a particular material or surface finish for any part of the crib.

The broken lines in the drawings are directed to environment. None of the broken lines forms a part of the claimed design.

1 Claim, 6 Drawing Sheets
